UNITED STATES PATENT OFFICE.

JOHN A. HUBER, OF LANCASTER, PENNSYLVANIA.

ADJUSTABLE PIVOT-BEARING.

1,071,746.

Specification of Letters Patent. Patented Sept. 2, 1913.

Application filed March 29, 1911. Serial No. 617,586.

To all whom it may concern:

Be it known that I, JOHN A. HUBER, a citizen of the United States, residing at Lancaster, in the county of Lancaster and State of Pennsylvania, have invented certain new and useful Improvements in Adjustable Pivot-Bearings, of which the following is a specification, reference being had therein to the accompanying drawing.

10 This invention relates to an adjustable pivot-post or thrust bearing, and more particularly to the mechanism for compensating for the wearing away of the parts.

It is the general practice in the construction of ice-cream freezers to provide a pivot post which is provided with attaching flanges for securing to the bottom of the tub, and as the bearing socket on the bottom of the can becomes worn, the can will become 20 lower in the tub which will bring the gearing, which rotates the can, out of mesh, unless the flanged pivot post is removed and packing placed between it and the tub bottom, which is unsatisfactory in many ways.

25 To obviate this trouble, I have constructed an adjustable pivot post that is cheap, durable and efficient, and that may be used with most styles of freezers now in use.

With these and other objects in view, my 30 invention consists in certain construction and combination of parts that will herein-after be fully described and claimed in the annexed specification, and illustrated in the accompanying drawings, which form a part 35 of this application, and in which like figures of reference refer to corresponding parts in all of the views; but it is fully understood that while I have here described my invention as shown, that I do not confine myself 40 to the exact design, as slight changes may be made in the construction and arrangement of the several parts without departing from the spirit of the invention.

In the drawings: Figure 1 is a partial 45 detail vertical sectional view of a freezer embodying my device, and showing the parts before much wear has taken place. Fig. 2 is a similar view, showing the position of the parts after the socket member 50 has become worn, and the method of compensating for said wear. Fig. 3 is a top plan view of the device.

Referring to the drawings, the usual freezer tub is indicated by the sides 1, and the bottom 2; and the rotatable can by the 55 numeral 3. The tub bottom 2, is provided with a central orifice 4, within which is mounted the socket member 5, having the radial attaching arms 6, by which it is secured to the tub bottom 2, by the screws 7; 60 a water-tight packing material 8, being disposed between. Said member 5, is provided with a socket 9, which communicates with a screw hole 10, in the bottom of said member. Within said socket 9, is mounted a 65 pivot post 11, which is formed with a flanged head 12, having a cone-shaped pivot 13, thereon; and a bore 14, screwthreaded to receive the securing screw 15.

When the device is first put into use, the 70 pivot post 11, is secured in the socket 9, as shown in Fig. 1, with one washer 16, placed under the flanged head 12, and in a seat 17, formed in the top of said member 5. But as the bearing member 18, which is attached 75 to the can 3, becomes worn, one or more additional washers 19, may be employed, as shown in Fig. 2, which keeps the can 3, the proper distance from the bottom 2, to give the operating gears the required mesh. 80

Having thus described my invention what I claim as new and desire to secure by Letters Patent is:—

In an adjustable pivot bearing, the combination with a bearing member, of a socket 85 member having a counterbored seat thereon, and radial attaching arms provided with attaching means, a pivot post having a screw-threaded bore mounted in said socket member, said pivot post member having a 90 flanged head and a cone-shaped pivot, a screw adjustably securing said socket member and pivot post together and a washer interposed in the counterbored seat between the flanged head and socket member. 95

In testimony whereof I affix my signature in presence of two witnesses.

JOHN A. HUBER.
